UNITED STATES PATENT OFFICE.

GEORGE E. STEINBRENNER, OF IRVINGTON, NEW JERSEY, ASSIGNOR TO HANZL & STEINBRENNER, OF NEWARK, NEW JERSEY, A FIRM COMPOSED OF WILLIAM F. HANZL AND GEORGE E. STEINBRENNER.

DESIGN FOR A FINGER RING, BADGE, EMBLEM, PIN, OR SIMILAR ARTICLE.

• 61,123.

Specification for Design. Patented June 20, 1922.

Application filed January 28, 1922. Serial No. 412. Term of patent 14 years.

To all whom it may concern:

Be it known that I, GEORGE E. STEINBRENNER, a citizen of the United States, and a resident of Irvington, in the county of Essex and State of New Jersey, have invented a new, original, and ornamental Design for a Finger Ring, Badge, Emblem, Pin, or Similar Article, of which the following is a specification, reference being had to

the accompanying drawing, forming part thereof.

The figure is a plan view of a pin showing my new design.

I claim:

The ornamental design for a finger ring, badge, emblem, pin or similar article, as shown.

GEORGE E. STEINBRENNER.
